Re. 15,621

UNITED STATES PATENT OFFICE.

FRANK E. MARCY, OF LOS ANGELES, CALIFORNIA.

ROLLER MILL.

Original No. 1,361,601, dated December 7, 1920, Serial No. 273,097, filed January 25, 1919. Renewed October 13, 1920, Serial No. 416,773. Application for reissue filed November 29, 1922. Serial No. 604,093.

DIVISION A.

To all whom it may concern:

Be it known that I, FRANK E. MARCY, a citizen of the United States, residing at Los Angeles, in the county of Los Angeles and State of California, have invented certain new and useful Improvements in Roller Mills, of which the following is a specification, reference being had to the accompanying drawings, forming a part hereof, the same being a division of an application filed on the 16th day of November, 1922, Serial No. 601,240, for reissue of my Patent No. 1,361,601, dated December 7, 1920.

The present invention is directed to improvements in roller (or rod) mills which, as well understood in the art, belong to that class of reducing or disintegrating apparatus wherein the material is reduced by means of freely moving reducing bodies in the form of rods or rollers extended longitudinally substantially the length of the reducing compartment of the mill, the latter being in the form of a suitable tumbling barrel, drum, or equivalent tubular container or treatment vessel rotated about a fixed axis, the opposite extremities of the barrel being provided respectively with intake or feed, and discharge openings for the material. The present improvement is concerned with that type of mill in which the discharge end is left open and unobstructed (in contradistinction to the trunnion overflow type of mill) for the passage of the material therethrough and for the purpose of affording access to the interior of the mill at all times, and permitting inspection of its contents at any stage of the reducing operation. A mill of the open end type here referred to is provided with a flange or diaphragm at the point of discharge, said flange serving to build up or raise the pulp line in the mill and thereby permitting the charge of material to be subjected to the reducing action of the rods (or their equivalent) for a somewhat longer period of time than would be the case were the flange dispensed with and the pulp line allowed to drop. It is desirable in a mill of the character referred to, to provide means for preventing the reducing bodies from being projected out of the mill through the open discharge end, or through the available opening defined by the inner edge of the flange

aforesaid; and in the present embodiment of my invention I resort to a suitable rod-intercepting door or guard so mounted that while the free and uninterrupted discharge of the material from the mill will be permitted, the door serves as an effective barrier against the projection or precipitation of the reducing bodies from the mill. This guard partakes of the nature of a hinged door which may be manipulated at will so as to uncover the opening defined by the inner edge of the flange for purposes of inspection of the mill contents or for the purpose of gaining access to the reducing compartment of the mill at any stage of the reducing operation.

The present improvement is characterized mainly by simplicity of construction and effectiveness in operation, and advantages of the improvement will be clearly apparent from the following detailed description in connection with the accompanying drawings in which—

Fig. 1 represents a side elevation of a mill with parts broken away, showing my invention embodied therein.

Fig. 2 is a vertical middle longitudinal section of the barrel of the mill.

Fig. 3 is an end view of Fig. 2.

Referring to the drawings:

D represents a (preferably) cylindrical container, drum, tumbling barrel or equivalent tubular member slightly pitched to the horizontal h , the reducing compartment C of the barrel containing the usual complement of reducing bodies which in the present example are in the form of longitudinally extended, loose, reducing rods or rollers 1 free to tumble in the barrel as the latter rotates in the operation of the mill, only a portion of the entire complement of rods being herein illustrated. The wall liner 2 is provided with inclined lifters 3 which operate to first lift the rods and then release them in such a way as to cause the rods to tumble or precipitate away from the discharge opening of the mill, the rods being maintained permanently in the reducing compartment C through the combined action of the pitch of the mill, the lifters 3, the flange 4 at the open discharge end of the mill, which likewise serves to raise or build up the pulp line, and the guard or rod-intercepting plate or

door. In the present example the mill is provided with a hollow feed or intake trunnion 5 equipped with a conventional scoop feeder 6, which scoops up the pulp from a suitable launder 7, the material discharged from the mill being caught in a launder 8 as well understood in the art.

In the present improvement the guard or rod-intercepting member is carried by the 10 barrel D and assumes the form of a door 9 in front of the flange 4 and preferably hinged to the barrel, the diameter of the door being such that it will fit in the opening defined by the inner edge of the flange and thus close 15 said opening. The door is hinged to the barrel by means of a pivot pin *a* and is locked normally closed by means of a cap screw *d*, as shown in Figs. 1 and 2. The flange 4 is formed outward of its inner edge 20 with an annular interrupted discharge slot or passage-way *u* at such a point as to raise the pulp line *x* the desired degree, so that in the rotation of the barrel the reduced material will be discharged continuously 25 through said annular slot or passage-way. The passage-way or slot through the flange extends circumferentially, and at the outer face of the flange this circumferential passage-way or slot is interrupted at intervals 30 by intact portions of the flange or its equivalent, but this interruption in no wise interferes with the free discharge of the pulp from the mill. Preferably, the periphery of 35 the door is made beveled or conical and the inner edge of the flange correspondingly formed to receive the door. The pulp which builds up to the dotted line *x* indicated in Fig. 1 flows through the slot in the flange and into the launder 8 as indicated by the 40 arrows.

As stated above the function of the door or guard 9 is to intercept any rod tending to precipitate out of the mill during the reducing operation; but the door may be 45 swung open at any stage of the reducing operation to allow for the inspection of the mill contents, to make the necessary repairs, and the like.

The operation is the same as in all mills 50 of the general type or class to which the present mill belongs. The mill or barrel is given a rotation in the direction indicated by the arrows in Fig. 1, the wall nearest the reader sweeping upward while the wall 55 farthest away is descending. The reducing rods 1 tumble freely across the reducing compartment C, but since in their tumbling movements they are constantly being directed away from the discharge opening by the combined action of the pitch of the mill, and the inclined lifters, it follows that the rods 60 will remain normally out of contact with the door or guard 9, but any rod which happens to strike the door 9 will of course necessarily be intercepted and prevented from

falling out of the mill. The impact of the rods against the door is however not frequent as the rods are in the main kept in the mill by the pitch of the mill, by the deflecting action of the lifters 3, and by the 70 flange 4. The pulp enters the reducing compartment C through the hollow feed trunnion 5 at one extremity of the barrel and the finished product discharges as previously indicated through the circumferential passage-way in the flange at the opposite extremity of the barrel and into the launder 8. 75

The door or rod-intercepting member or plate 9 is, it will be observed, disposed across the rotation axis of the mill or barrel, said axis passing preferably through the center of the door, and as the flange 4 extends inwardly from the wall of the barrel towards the rotation axis, the door closes across the plane of disposition of the flange. 80 85

In the construction described, the discharge slot for the material conforms to the position desired for the pulp line, which, of course may be raised or lowered according to circumstances, and according to conditions to be met with in practice. The present invention of course is not to be restricted in its application to mills with a pulp line of the particular height indicated herein, but is to be understood as applicable to mills having any range of pulp line positions from the lowest to the highest which may be tolerated in practice. 90 95

Having described my invention, what I claim is:

1. In a mill of the character described, a tumbling barrel having a feed end and a discharge end respectively at its opposite extremities and adapted to contain longitudinally extending loose freely movable reducing bodies, an inwardly projecting flange at the discharge end of the barrel, and a guard closing across the plane of disposition of the flange and movable at will without disturbing the other parts of the mill to permit access to the interior of the barrel, said flange being provided with a passage-way outward of its inner edge for effecting the direct discharge of material from the barrel. 100 105 110

2. In a mill of the character described, a tumbling barrel having a feed end and a discharge end and adapted to contain longitudinally extending loose freely movable reducing bodies, and inwardly projecting flange at the discharge end of the barrel, and a guard closing across the plane of disposition of the flange and rotatable with the barrel and movable at will to permit access to the interior of the barrel, said flange being provided with a passageway outward of its inner edge for effecting the direct discharge of material from the barrel. 115 120 125

3. In a mill of the character described, a tumbling barrel having a feed end and a

discharge end, an inwardly projecting flange at the discharge end of the barrel, and a door closing across the plane of disposition of the flange and movable at will independently of the flange, to permit access to the interior of the barrel, said flange being provided with a passageway outward of its inner edge for effecting the direct discharge of material from the barrel, said passageway being interrupted at the outer side of the flange.

4. In a mill of the character described, a tumbling barrel having a feed end and a discharge end, an annular inwardly projecting flange at the discharge end of said barrel defining an opening at said end, and a door fitting within said opening, said flange being provided with a passage-way outward of said opening for effecting the direct discharge of material from the barrel.

5. In a mill of the character described, a tumbling barrel having a feed end and a discharge end, an inwardly projecting flange at the discharge end of the barrel, and a hinged door closing across the plane of disposition of the flange, said flange being provided with a passage-way outward of its

inner edge for effecting the direct discharge of material from the barrel.

6. In a mill of the character described, a tumbling barrel having a feed end and a discharge end, an inwardly projecting flange at the discharge end of the barrel, and a hinged door closing across the plane of disposition of the flange and rotatable with the barrel, said flange being provided with a passageway outward of its inner edge for effecting the direct discharge of material from the barrel.

7. In a mill of the character described, a tumbling barrel having a feed end and a discharge end, an inwardly projecting flange at the discharge end of the barrel, and a hinged door closing across the plane of disposition of the flange and rotatable with the barrel, said flange being provided with a circumferential passage-way outward of its inner edge for effecting the direct discharge of material from the barrel.

In testimony whereof, I have affixed my signature hereto.

FRANK E. MARCY.
